UNITED STATES PATENT OFFICE.

WEBB JAY, OF CHICAGO, ILLINOIS.

MULTIPLE-ACTION VACUUM FEED DEVICE.

1,293,790.

Specification of Letters Patent. Patented Feb. 11, 1919.

Application filed April 8, 1918. Serial No. 227,363.

To all whom it may concern:

Be it known that I, WEBB JAY, a citizen of the United States, residing at Chicago, in the county of Cook and State of Illinois, have invented certain new and useful Improvements in Multiple-Action Vacuum Feed Devices, of which the following is a specification, reference being had to the accompanying drawings, forming a part thereof.

The purpose of this invention is to provide a liquid pumping system of the vacuum feed type in which a plurality of vacuum feed chambers are arranged to operate simultaneously from a common source of suction and upon a common supply of liquid, alternating or overlapping as to their respective filling and discharging periods, so that the suction may be more fully utilized than when only a single vacuum chamber is operated. The invention involves the various features of construction and certain relations of parts hereinafter described and shown in the drawings as indicated by the claims.

In the drawings the invention is presented in a single side elevation, in which, however, the parts are principally shown in vertical section, the apparatus chosen for purposes of illustration comprising only two vacuum chambers associated together, although the invention contemplates any desired number of chambers so associated.

The outer chamber, 1, is the usual auxiliary chamber of a vacuum feed device, except that it is especially designed to contain a plurality of vacuum chambers, 2, each shown as provided with a suction pipe, 3, and air vent pipe, 4, controlled respectively by valves, 5 and 6, each set of valves being operated by an individual float, 7, in the chamber, 2, connected to the valves by a familiar system of levers. It may be understood that the suction pipe, 3, may lead from a common source of suction and may be suitably joined into a single conduit in the vicinity of the auxiliary chamber, 1, such connection, however, being of an obvious nature, not shown in the drawings. The liquid supply is indicated, however, as provided with a single pipe, 8, terminating in a T-fitting from which branch pipes, 9, lead to check valve fittings, 10, each mounted in the upper portion of one of the vacuum chambers, 2.

In accordance with the well understood

principle of a vacuum feed system, it will be evident that with the valve, 6, closed, and the valve, 5, open, the suction acting through pipe, 3, will exhaust the air in the chamber, 2, causing an inflow of liquid from pipe, 8, past the inwardly opening check valve, 10, by reason of the fact that the main supply tank from which the pipe, 8, leads, is under atmospheric pressure, which is sufficiently greater than the reduced pressure in the chamber, 2, to cause the liquid to flow up from the lower supply receptacle through the pipe, 8, and to discharge into the chamber, 2, as indicated. As the chamber, 2, becomes filled, the float, 7, rising to its upper limit moves the levers from the position shown in the right hand chamber, 2, to the position of the levers shown in the left hand chamber in the drawings, whereby the suction valve, 5, is closed and the atmospheric air valve, 6, is opened. The inrush of air rapidly dissipating the partial vacuum in the chamber, 2, and equalizing the interior pressure with that within the outer chamber or receptacle, 1, which is constantly open to atmosphere, permits discharge of the liquid contents of the chamber, 2, by gravity through the check valve, 11 or 12, as the case may be, according to which of the chambers, 2, is being considered. Where only a single vacuum chamber, 2, is employed, the time required for this equalization of pressure within the chamber, 2, and discharge of its contents into the chamber, 1, constitutes an idle period during which the suction is not utilized for lifting any liquid from the main supply tank through pipe, 8; but it will be evident that by using two or more vacuum chambers, 2, their operation may be made to alternate in such a way that the suction will be utilized at all times for lifting some liquid through pipe, 8, resulting in a more efficient use of the suction available and, in the case of an internal combustion engine, resulting in a more uniform effect on the engine suction and action of the carburetor.

It will be evident that if the filling and discharging periods of the two or more vacuum chambers are to be alternated with respect to each other, an open connection between the chambers through branch pipe, 9, without the use of the check valves, 10, would tend to defeat the operation because the suction acting on one chamber would act simultaneously on each and every other

one of the vacuum chambers, in many cases defeating the discharge of the contents even after such other chambers had become filled, and had opened their air vent valves, 6, and at least greatly hindering the proper operation. For this reason the check valves, 10, are provided and they permit each of the chambers, 2, to operate independently of the other. Since the duration of the period of filling and the period of discharge is affected by several factors including the exact size and buoyancy of the float, the exact tension of the spring, the particular size of the valve ports and even the weight of the valves themselves, it seldom happens that any two vacuum chambers will have exactly the same period of operation even under similar conditions, so that by merely assembling two or more such units at random, it will be found that they will not usually operate in unison, but will tend to get out of timed relation to each other and will overlap each other as to their periods of filling and discharge. To render this result altogether certain, however, it is only necessary to make the discharge valves, 11 and 12, of slightly different capacities, so that one chamber will always discharge more rapidly than the other. In the drawing the valve, 11, is shown as being of somewhat smaller size than the valve, 12, and it will therefore discharge more slowly than the latter. It will be understood that any other expedient may be employed for defeating unison of operation of the two or more vacuum chambers.

The liquid being accumulated in the common auxiliary receptacle, 1, will flow therefrom by gravity through the discharge pipe, 13, since the chamber, 1, is constantly open to atmospheric pressure through ducts, 14,

leading into the cap plate for communication with the air vents, 4.

I claim:

1. In a liquid feeding system comprising a source of suction, a plurality of chambers each communicating therewith and having also an atmospheric vent, together with liquid-controlled means in each chamber for alternating the dominance of atmospheric pressure and suction therein, whereby said system is adapted to fill said chambers by drawing liquid from a receptacle at a lower level than said chambers and to discharge it from each chamber during the period of atmospheric dominance therein, a common source of liquid supply and conduits therefrom to all said chambers, together with means for preventing intercommunication of said chambers through such conduits.

2. In the combination set forth in claim 1 the means for preventing intercommunication of the chambers comprising automatic check valves controlling the portions of said conduits associated with the respective chambers and opening toward the same.

3. In the combination set out in claim 1, the respective chambers with their associated parts involving differences of detail to prevent periodic unison in their operation.

4. In the combination set out in claim 1, means for insuring differences in the discharge or filling periods of the respective chambers to avoid unison of operation.

In testimony whereof, I have hereunto set my hand at Chicago, Illinois, this 3rd day of April, 1918.

WEBB JAY.
